UNITED STATES PATENT OFFICE.

BENJAMIN A. GROVER, OF MOMENCE, ILLINOIS.

ABDOMINAL SUPPORTER.

Specification of Letters Patent No. 24,630, dated July 5, 1859.

To all whom it may concern:

Be it known that I, BENJAMIN A. GROVER, M. D., of Momence, in the county of Kankakee and State of Illinois, have invented a new and useful instrument for supporting the abdominal wall and other parts of lying-in women after delivery, called Grover's Abdominal Spring-Pad for Lying-in Women; and I do hereby declare that the following 10 is a full, clear, and exact description of the same, reference being had to the accompanying drawing, making part of this specification.

Figure 1 is a perspective view of the instrument, with its several parts arranged in the position they assume in relation to each other when applied to the person. Fig. 2 is a front elevation of the adjustable spring frame of ditto. Fig. 3 is a horizontal section of the said adjustable spring frame, with the expanding and contracting canvas or other cloth attached thereto.

Similar letters in the figures refer to corresponding parts.

This instrument is designed to take the place of the towel bandages usually applied to the person after delivery, and is for the purpose of supporting the abdominal wall when in a flaccid condition and retaining the uterus and other contiguous organs *in situ*, at the time when there is constant tendency to displacement and is so constructed as to enable it to be adjusted and adapted to any size or condition of person, 35 and tightened and loosened above and below as occasion may require, and otherwise adjusted to suit the condition and position of the patient by the patient herself.

To enable others skilled in the art to 40 make and use my invention I will proceed to describe its construction and operation.

The nearly upright center steel spring bar A, of the spring frame, is provided with a set screw 1, at its upper end, which passes 45 through a transverse tongue on said bar, inserted in slots formed in the end of curved horizontal steel bars B, overlapping each other, and connected together by loops C, secured to their ends through which they 50 respectively pass. This enables the bars B to be elongated or contracted, and secured at any desired length, by the shoulder of the set screw 1. To the opposite ends of the spring bars B, are secured at a slightly 55 obtuse angle, two flat bars D on the front surface, next the lower end of which, are

formed tongues which enter and slide in corresponding slots s, formed in other flat spring sliding bars E, which overlap them in front, being connected together by loops F, at the upper ends of the bars E, through which the bars D, pass, and guided in their sliding movements by the tongues at the lower ends of the said bars D, and button head secured to the same.

The lower ends of the bars E, are slightly curved toward each other and are jointed by pins, to the upper ends of segmental spring bars G, whose lower ends are overlapped by other segmental spring sliding slotted bars H, which are connected to, and guided in their movements over the bars G, by loops I, and slots J, of the bars H, and tongues and button head of the bars G, in the same manner that the bars E, are connected to, and guided in their sliding movements over the bars D.

The segmental bars H, are jointed by pins to the ends of a short segmental bar K, secured at its center to the lower end of a spring slotted bar L, which extends upward therefrom at a right angle, and overlaps the lower curved and slotted ends of the center bar A to which it is attached by a loop l at the end, through which the said bar A passes, and a set screw entering a tongue projecting from the lower end of the center bar A, and moving in the slot of the bar L.

To near the lower curved end of the bars E, are secured the end of curved horizontal spring bars M, which overlap and slide over each other at their opposite ends, where they are slotted and provided with loops, similar to those on the ends of the 90 correspondingly curved bars B, for guiding them in their sliding movements, being clamped firmly at any point of their movements by a clamp screw 2, entering a nut having a tongue on its face, which enters the 95 slot in the said bars M. The concave portion of the adjustable spring frame thus formed, which, when applied, is next the abdomen, is covered entirely by a canvas or other cloth Z, whose edges are brought over 100 the upper, lower and side bars of the spring frame, and are gathered and sewed or hemmed, to form a casing over an endless, round, india rubber cord c, whose elasticity is made to always draw the said canvas or 105 other cloth, over the edges of the top, bottom and side bars of the spring frame, and

keep the portion of the same next the abdomen, to the proper degree of tension.

To the set or clamp screw 2, in front of the spring frame, is secured the center of a short strap N, of canvas or other suitable material which extends over the curved bars M, and is provided with buckles at its ends, to which are buckled other straps O, formed on, or attached to the ends of tapering bands, 10 which are attached by shirred rubber bands, to a broader piece of cloth or pad O', shaped somewhat after the form of a diamond, and designed to rest upon the spine, and parts on either side of the same, of the person to 15 which the instrument is applied. Each of the tapering bands between the shirred rubber bands, and the straps O, are provided with two straps P, P', which are perforated with a series of holes, and are connected at 20 their shirred rubber ends to the said straps O, and extend therefrom at obtuse angles, upward and downward, respectively to the button head of the screw 1, at the upper end of the steel spring frame, and the button head 3, at the lower end of the same, to 25 which they buttoned.

The instrument is applied and operated in the following manner: The straps P, P', O, on the side of the spring frame, are first 30 detached from their respective button head, above, and below, and the buckle on one end of the strap N, and the said spring frame is then either enlarged or contracted, by un-clamping the set or clamp screws 1, 2 which 35 admits of the upright center and horizontal bars A, L, B, M and the side and lower curved bars D, E, G, H, sliding past each other, until the pad formed by the canvas or other cloth z, drawn over the outer edges 40 of the spring frame by the elastic rubber cord c, corresponds with the size and form of the abdomen to which it is to be applied. The spring frame thus padded is placed against the abdominal wall, either over a 45 night dress or beneath it, as may be desired, with the lower semicircular portion resting immediately above the pubric bone after which the straps P, P', O, are secured as on the opposite side, to the proper gentle 50 degree of tightness, always observing the precaution to draw the lower straps P', a little tighter than the corresponding upper ones P, in order that the greater pressure 55 may be exerted from the lower part of the spring pad z, upward. When thus properly adjusted the back pad portion O', of the bands b, rests upon the spine, in such manner as to give it support.

From the foregoing it will be observed 60 that a greater or less pressure, as occasion may require, can be given to any particular portion of the abdominal wall, by enlarging or reducing the respective sliding portions of the instrument. By drawing the lower 65 semicircular part outward, or enlarging it a

little, such a concavity may be produced in the instrument, that when the lower strap P', is drawn a trifle the tightest it will give a complete support just below the uterus—a feature that is demanded at a time when the uterus is much enlarged and weakened.

The superiority of this instrument over the ordinary system of bandaging, consists mainly in its easy adaptability to size and position, the convenience with which it can be applied, and the complete support that it gives to the abdominal wall while in a flaccid condition after delivery, and the retention of the uterus and abdominal organs, one and all, *in situ*, at a time when there is constant tendency to displacement. These desirable results are obtained without making pressure at any point where it is useless, or not absolutely required, as in the case with the towel bandage heretofore employed, which necessarily bandages the entire body to give it the proper pressure in front. With the towel bandages it is necessary to extend them around the hips, and the portion of the body above, and as the former is in all cases of greater bulk than the latter, the pressure of the bandage was from above downward, rather than from below upward, inducing, rather than preventing displacement. Again, the ordinary system of bandaging being difficult of adjustment, the attention of a nurse was indispensable when the patient required the bandage readjusted, tightened, or loosened. With my abdominal instrument, the patient can herself tighten or loosen the upper and lower and center straps P, P', O, to suit circumstances or position. If the patient desires to assume an erect posture, as is frequently the case, the lower strap P', can be made as tight as necessary for preventing any displacement of the organs while moving, after which the pressure can be taken off.

The concavity of the instrument, the material of which it is composed,—spring bars—the elasticity given to the border or edge of the canvas or other cloth, the adjustable character of the straps P, P', O all tend to insure an even and complete pressure to every part of the abdominal wall. They moreover enable greater pressure to be given at one portion of the abdomen, and less at others, when occasions demand. The expanding and contracting character of the spring frame is also desirable, as it adapts it to be readily applied to any size or form of person.

This instrument will be found useful in cases of *prolapsus uteri*, when applied to the person in the manner before detailed.

What I claim as new and desire to secure by Letters Patent is—

1. Constructing an adjustable spring steel frame of the form described, by combining,

arranging and securing together a series of spring bars, substantially in the manner and for the purpose described.

2. I claim covering the concave portion of said frame, with a canvas or other cloth *Z*, whose edge or border is gathered and drawn together over the outside edges of the said spring frame, by an india rubber or other elastic cord *e*, so as to give the covering portion of said canvas or other cloth, the character of an elastic cushion, no matter what may be the extent of the contraction or expansion of the spring frame, as before described.

3. I also claim attaching the upper and lower straps *P*, *P'*, which respectively branch upward and downward from the band *b*, of the main strap *s*, *o*, at the points of the spring frame, and in the relation to each other, and the center or main straps *s*, *o*, described and represented, so as to give an upward pressure to the spring frame, and for the other purposes set forth.

BENJN. A. GROVER.
